UNITED STATES PATENT OFFICE.

WALTER N. EDWARDS, OF PROVIDENCE, RHODE ISLAND.

MOVABLE RACER OF BRAIDING-MACHINES.

No. 926,106.

Specification of Letters Patent.

Patented June 29, 1895.

Application filed June 22, 1893. Serial No. 220,233.

To all whom it may concern:

Be it known that I, WALTER N. EDWARDS, a citizen of the United States, residing at Providence, county of Providence, and State 5 of Rhode Island, have invented a new and useful Improvement in Movable Racers of Braiding-Machines, of which the following is a specification.

This invention has reference to an improvement in braiding machines and more particularly to an improvement in the movable racers of braiding machines.

In movable racers of braiding machines as heretofore constructed, a cast iron tension 15 weight sliding on its support abuts directly against the lower end of a cast iron latch also adapted to slide on the support. The latch above the tension weight has an arm extending over the bobbin adapted to engage with the teeth on the upper or head end of the bobbin and the upper end of the support is contracted to allow of the placing or removal of the latch and tension weight. The draft of the thread on the tension weight 20 lifts the weight and latch. The draft of the thread may lift the latch beyond its normal operative position and into the contracted portion of the support, from which it is liable to and does at times fall outward from 25 the support, thereby disintegrating the thread tension and delivery mechanism. The latch in falling into the machine is also liable to break some operative part of the machine. The weight of the cast iron tension weight 30 and latch increases the weight of the racer, thereby increasing the friction of the racers in their operative movements in the machine.

The object of my invention is to improve the construction of the thread tension and 40 delivery mechanism of a racer for braiding machines, whereby the tension weight is improved and lightened by forming the same of sheet metal, the usual form of latch adapted to slide on the support discarded 45 and a lighter sheet metal spring actuated latch substituted, the operation of the thread tension and delivery mechanism improved and the friction of the racer in the machine decreased by lightening the weight of the 50 racer.

My invention consists in the peculiar and

novel construction of the thread tension and delivery mechanism of a racer for braiding machines, said mechanism having details of construction, as will be more fully set forth 55 hereinafter and claimed.

Figure 1 is a side view of a movable racer for braiding machines provided with my improved thread tension and delivery mechanism and showing the same in its normal 60 operative position. Fig. 2 is a detail view of the thread tension and delivery mechanism looking at the outer face with the support broken away from the frame of the racer. Fig. 3 is a vertical sectional view taken on 65 line 3-3 of Fig. 2 through the support and tension weight. Fig. 4 is a transverse sectional view taken on line 4-4 of Fig. 1, showing the means of holding the latch in its operative position, and Fig. 5 is a detail 70 transverse sectional view taken on line 5-5 of Fig. 2 through the support and tension weight.

In the drawings, *a* indicates the frame of the racer, *b* the tension weight, *c* the latch, *d* 75 the bobbin and *e* the thread.

The frame *a* has the usual stub spindle 6 for the lower end of the bobbin, as shown in broken lines in Fig. 1, a vertical support 7 having the lower contracted portion 8, the 80 side slot 9 leading to the guide eye 10, the upper contracted portion 11 for placing or removing the tension weight *b*, the vertical slot 12 for the latch *c*, the guide eye 13 on its upper end, the bracket 14 adjacent its upper 85 end supporting the vertical bearing 15, a vertical stem 16 in the bearing 15 and having a stepped head 17 for the upper end of the bobbin *d*, as shown in broken lines in Fig. 1, a coiled spring 18 on the stem 16 intermediate the bearing 15 and the head 17 and a pick 19 at the base of the vertical support 7. The bobbin *d* may be removed by pushing up the bobbin against the tension of the spring 18 until the lower end of the 95 bobbin clears the end of the stub spindle 6.

The tension weight *b* is constructed from sheet metal and shaped to form the transversely curved body portion 20 which forms a space 21 between the support 7 and the tension weight *b* for the thread *e* and has a guide eye 22 connected to the edge of the

body portion 20 by a slot 23, the side tips 24 loosely fitting the support 7 and forming a vertical opening 25 slightly wider than the contracted portion 11 of the support 7, an upwardly extending end 26 adapted to engage with the latch *c* and a flat lower end 27 adapted to engage with the notch 19 at the base of the support 7 and forming the outwardly-extending side wings 28 28, as shown in Figs. 2, 3 and 4. The guide eye 22 in the tension weight *b* comes centrally under the guide eye 10 in the support 7 when the tension weight is in its normal operative position.

15 The latch *c* is in the form of an arm 29 stamped from sheet metal and shaped to have the square end 30 with the central hole 31 for the stem 16, the downwardly-extending side lip 31' and the forked end 32. The latch *c* is held in its operative position intermediate the head 17 on the stem 16 and the lower end of the coiled spring 18 by the stem 16 extending through the hole 31 in the latch and extends through the slot 12 in the support 7, thereby bringing the forked end 32 into a position for the upwardly extending end 26 of the tension weight *b* to engage with and lift the latch.

30 The bobbin *d* has the usual teeth 33 33 on its upper or head end with which the side lip 31' on the latch engages, as shown in Figs. 1 and 4.

In the operation of my improved thread tension and delivery mechanism the thread 35 *e* coming from the bobbin *d* passes through the guide eye 10 in the support 7, then downward and through the guide eye 22 in the tension weight *b*, then upward through the guide eye 13 in the top of the support 7 to the point where the several threads in the machine are braided together. The draft of the thread as it comes from the bobbin raises the tension weight *b*. This in turn through the upwardly-extending end 26 engaging with the forked end 32 of the latch *c* raises the latch *c* against the tension of the coiled spring 18, thus releasing the lip 31 on the latch from the teeth 33 on the bobbin, and allowing the bobbin to revolve one tooth. The latch *c* now falls by gravity and through the tension of the spring 18 and catches the next tooth on the bobbin. These operations are repeated indefinitely, delivering a predetermined amount of thread for each upward movement of the latch. The latch *c* is securely held in its operative position and forms a permanent member of the racer. When the thread *e* breaks the tension weight *b* falls by gravity, the lower end 27 of the tension weight enters the notch 19 and the side wings 28 28 on the tension weight engage with and operate the usual stop motion to stop the machine.

65 The tension weight *b* and latch *c* are made as light as possible by constructing the same

of sheet metal. The required tension on the thread *e* is attained by the tension of the coiled spring 18 on the latch *c* and the racer as a whole is lightened in weight, thereby decreasing the friction of the racer in the machine. The tension weight *b* may be removed from the contracted portion 11 of the support 7 by forcing the latch upward to the top of the slot 12 in the support.

Having thus described my invention, I claim as new and desire to secure by Letters Patent;

1. A racer for braiding machines comprising in combination with a bobbin, a vertical support having a substantially reduced portion at its upper end and a vertical slot formed between the edges of said reduced portion, a tension weight having rearwardly and inwardly turned flanges for slidably engaging said vertical support and adapted to be placed in position over said reduced portion, a rigid bracket secured to said support and projecting over said bobbin, said bracket being provided with a spring pressed vertical stem to engage the bobbin at its upper end, and a latch carried by said spring, said latch comprising a member provided at one end with an opening for slideable engagement with said stem, a downturned lip for engagement with the toothed end of said bobbin, and a bifurcated end adapted to project through and engage said vertical slot in said support and adapted to operatively rest on the upper end of said tension weight.

2. A racer for braiding machines, comprising in combination with a threaded bobbin, a vertical slotted support, a bracket provided with a spring pressed stem for engaging the upper end of said bobbin, a sheet metal tension weight provided with a guide eye and having rearwardly and inwardly turned flanges for slidably engaging said support, and a sheet metal latch, having an opening for slideable engagement with said vertical stem, a downturned lip adapted to engage the toothed end of said bobbin, and a bifurcated portion projecting through and slidably engaging with the slotted support, and resting on the upper end of said tension weight, whereby said latch is operated to release said bobbin by the upward tension exerted by the thread on said tension weight.

3. A racer for braiding machines comprising in combination, a frame, a bobbin removably carried thereon, a vertical support beside said bobbin having a reduced portion at its upper end, a rigid bracket carried by said support at its upper end and carrying a spring pressed stem for engaging said bobbin, a tension weight carried by said support and a latch member carried on said stem below said spring for engagement with the said bobbin, said tension weight comprising a metallic sheet embracing said sup-

port and having a guide eye and rearwardly and inturned flanges, whereby said weight may be readily engaged or disengaged from said support by hinging said flanges opposite said reduced portion and either removed or replaced.

In testimony whereof I have signed my

name to this specification in the presence of two subscribing witnesses.

WALTER N. EDWARDS.
